UNITED STATES PATENT OFFICE.

WILLIAM T. MERSEREAU, OF SOUTH ORANGE, NEW JERSEY.

DESIGN FOR A BEDSTEAD.

SPECIFICATION forming part of Design No. 20,353, dated December 2, 1890.

Application filed October 27, 1890. Serial No. 369,512. Term of patent 3½ years.

To all whom it may concern:

Be it known that I, WILLIAM T. MERSEREAU, a citizen of the United States, residing at South Orange, Essex county, and State of New Jersey, have invented and produced a new and original Design for Bedsteads, of which the following is a specification, reference being had to the accompanying drawing, forming part thereof.

10 The accompanying drawing represents a bedstead constructed according to my design.

The leading feature of my design consists in the general outline of the ends or "head" and "foot" supports, so called, of the bedstead, the same being formed in a vertical line on one side, with the opposite side extending from a vertical line to the said vertical line in a continuous curved line, as shown in the drawing.

15 20 *a* represents the supporting posts or uprights on one side of the bedstead, and *a'* the

supporting posts or uprights on the opposite side of the bedstead. The latter extend vertically a short distance above the bed-supporting frame *a''*, and then extend at an angle in a continuous curved line toward the posts or uprights *a* and form the top rails of the bedstead.

I do not wish to confine myself to any particular design for the "filling-in," so called, consisting of the braces and other ornamental parts usually supported and located within the outer frame formed by the posts and upper connecting-rails, as shown; but

25 30 What I claim, and desire to secure by Letters Patent, is—

The design for a bedstead, as herein shown and described.

35 WILLIAM T. MERSEREAU.
